HIGH FREQUENCY INDUCTION HEATING COIL

Julius Hirshmann, Hillside, N. J., assignor to Radio Corporation of America, a corporation of Delaware

Application March 1, 1934, Serial No. 713,435

4 Claims. (Cl. 219—47)

My invention relates to a high frequency induction heating apparatus, and more particularly to improvements in the high frequency induction heating coils for heat treating the elements of an electron discharge device during its manufacture.

In the manufacture of electron discharge devices the occluded gases are removed from the metal elements or electrodes within the sealed envelope by heating the electrodes. This heating is usually done by subjecting the electrodes of the electron discharge device to a high frequency electromagnetic field which by induction heats them to a relatively high temperature, thereby driving out the gases.

The high frequency coil generally used to heat the electrodes of an electron discharge device, such as a radio tube, is of the solenoid type, the tube being placed inside and concentric with the turns of the coil. Some electrodes, such as certain types of anodes which are flat or boxlike, are difficult to heat, and require a large power input to the high frequency coil to bring about proper heating of the electrodes.

An object of my invention is to provide an improved type of induction heating coil which is simple, highly efficient and particularly adapted for heat treating flat or box type electrodes of an electron discharge device.

The novel features which I believe to be characteristic of my invention are set forth with particularly in the appended claims, but the invention itself will best be understood by reference to the following description taken in connection with the accompanying drawing in which:

Figure 1 shows a top view of a high frequency induction heating coil embodying my invention, with an electron discharge device in the coil in position to be heated.

Figure 2 shows a side view of the high frequency induction heating coil turned through 45 degrees and the electron discharge device shown in Figure 1, and

Figure 3 is a reduced vertical cross section of an induction heating coil embodying my invention with an electron discharge device in position to be heated, the high frequency field produced by the coil being diagrammatically indicated.

The preferred embodiment of a high frequency heating coil made in accordance with my invention and shown in the drawing comprises a plurality of turns 10, preferably of copper tubing the turns being electrically connected in

series. The turns have an elongated vertical transverse axis and are divided into two groups, each group comprising half the turns of the coil. The lower ends of each group are flared outwardly so as to provide oppositely disposed portions 11 and 12 lying in a plane substantially perpendicular to the plane of the longer vertical portion of the turns of the coil.

An opening is thus provided in the bottom end of the coil through which an electron discharge device 13, the elements of which are to be heat treated, can be positioned with the plane of the flat surfaces of the electrodes perpendicular to the longitudinal axis of the coil.

The terminal portions 14 and 15 of the coil 15 are electrically connected, in use, to the high frequency apparatus or generator (not shown) and to a cooling system, preferably water, (not shown) by means of coupling members 16 and 17.

While I do not wish to be restricted to any particular theory, I explain the effectiveness of a high frequency coil embodying my invention as follows:

The heating effect of a high frequency coil 25 upon a metal electrode in its field depends upon the amount of flux or the lines of force comprising the field of the coil which threads the electrode. With the usual helical or solenoid coil the field of the coil and the longitudinal 30 axis of the electrodes to be heated are substantially parallel, hence only a very small part of the field actually threads flat or box-like electrodes, and very little heating is obtained. Referring to Figure 3, it will be observed that the 35 flux or lines of force comprising the field of the coil and represented by the lines having arrowheads, are substantially perpendicular to the plane of the flat or box-like electrodes of the electron discharge device positioned within 40 the coil and that the field is most intense and uniform where it passes through the electrodes. Hence by the use of a coil embodying my invention the maximum amount of flux threads the electrodes to be heated for a given expenditure of energy and hence maximum heating 45 is obtained under these conditions.

It will thus be seen that I have provided a simple and effective high frequency heating coil particularly adapted for heat treating the electrodes of the electron discharge device of the type described during manufacture of the device.

While I have indicated the preferred embodiment of my invention of which I am now aware and have also indicated only one specific appli- 55

cation for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is,—

- 10 1. An induction heating coil comprising a plurality of turns electrically connected in series and lying in parallel planes, each coil having a corresponding portion flared outwardly to lie in a plane at an angle to said parallel planes whereby a pocket is formed within the turns of the coil for receiving an object extended perpendicularly to the longitudinal axis of said coil.
- 15 2. An induction heating coil comprising a plurality of turns electrically connected in series and lying in parallel planes, each coil having a portion flared outwardly to lie in a plane substantially perpendicular to said parallel planes whereby a pocket is formed within the turns of the coil for receiving an object ex-

tended perpendicularly to the longitudinal axis of said coil.

3. An induction heating coil comprising a plurality of turns electrically connected in series and having an elongated transverse axis, the turns being formed to have one end flared outwardly from the plane of the main portion of the turns to lie in a plane substantially perpendicular to the plane of the main portion of the turns whereby a pocket is formed within the 10

5

coil.

4. An induction heating coil comprising a plurality of turns electrically connected in series and having an elongated transverse axis, some of said turns having a portion at one end flared outwardly in one direction and the other turns having a portion at the same end flared outwardly in the opposite direction so that said flared portions are oppositely disposed and provide an opening to receive within said coil an object extended perpendicularly to the longitudinal axis of said coil.
